UNITED STATES PATENT OFFICE.

HENRY WEGMAN, OF ITHACA, NEW YORK.

MECHANICAL MUSICAL INSTRUMENT.

SPECIFICATION forming part of Letters Patent No. 251,977, dated January 3, 1882.

Application filed September 17, 1881. (No model.)

To all whom it may concern:

Be it known that I, H. WEGMAN, of Ithaca, in the county of Tompkins and State of New York, have invented a new and useful Improvement in Mechanical Musical Instruments, of which the following is a full, clear, and exact description.

My invention relates to musical instruments in which strips of perforated material are used for governing the admission of air to the reeds and pipes; and it consists in the novel construction hereinafter described and claimed, by means of which the reeds and pipes can be operated singly and in combination with the same perforated paper.

Reference is to be had to the accompanying drawings, forming part of this specification, in which similar letters of reference indicate corresponding parts in all the figures.

Figure 1 is a vertical section of my improved musical instrument, and Fig. 2 is a vertical section on line $x x$ of Fig. 1.

A is an air-chamber, fitted in its lower portion with bellows B, by which air is compressed in the chamber.

C is an air-tight cover, held in place on the chamber by buttons a, which permit removal of the cover.

D is an apertured reed-block fixed on the cover C, and carrying reeds b and pipes c.

d is a block attached to the under side of cover e, and apertured to correspond with block D and the several pipes and reeds thereon.

e is a similar block, sustained by springs f in chamber A, and pressed by such springs against the under side of block d.

In chamber A are rollers g g, sustained in suitable bearings; and h h are similar rollers sustained from cover C, so as to bear on the rollers g. One roller, g, has a crank-handle, i,

on its axis, outside the chamber, and there a connecting-rod, k, from the crank passes to the bellows B. The perforated sheet or strip of paper shown at l passes between rollers g h 45 and blocks d e. It is applied by removing the cover C, which leaves the rollers g and block e exposed.

In operation the handle I is turned, and the perforated sheet being thus fed between the blocks d e, the air passes to the reeds and pipes through the blocks D d whenever a perforation of the paper comes beneath the aperture of block d. Each perforation admits air to one reed and one pipe, and by suitable arrangement of the perforations any desired combination can be effected. The springs f press the block e on the perforated sheet, and thus prevent passage of air except by the perforations.

Having thus described my invention, I claim 60 as new and desire to secure by Letters Patent—

1. The combination of air-chamber A, containing feed-rollers g and apertured block e, with cover C, apertured block D, carrying reeds and pipes, apertured block d, and the 65 feed-rollers h, secured to the under side of cover C, substantially as shown and described.

2. The removable cover C, carrying reed-block D, apertured block d, and rollers h, combined with the air-chamber A, block e, and 70 rollers g in the chamber, substantially as shown and described.

3. The springs f and apertured block e, supported upon said springs, combined with the stationary paper-rollers g and removable rollers h, and apertured block d, all arranged to operate substantially as shown and described. 75

HENRY WEGMAN.
